CLAIM

The ornamental design for a vacuum attachment for collecting small particles, as shown and described.

DESCRIPTION

FIG. 1 is a perspective view of a vacuum attachment for collecting small particles showing our new design;

FIG. 2 is an exploded perspective view thereof with broken lines indicating a vacuum hose;

FIG. 3 is a side view of the screen portion shown in FIG. 2;

FIG. 4 is a bottom view of FIG. 3;

FIG. 5 is a side view of FIG. 3;

FIG. 6 is a side view of the opposite side of FIG. 3;

FIG. 7 is a top view of FIG. 1;

FIG. 8 is a side view of the attachment portion in FIG. 2;

FIG. 9 is a top view of FIG. 8;

FIG. 10 is a side view of the opposite side of FIG. 8; and,

FIG. 11 is a bottom view of FIG. 8.

The broken lines used in FIG. 2 of the drawings disclosure are for illustrative purposes only and form no part of the claimed design.
